Application October 4, 1944, Serial No. 557,174

16 Claims. (Cl. 187—29)

1 Our invention relates to control systems for elevators in which the cars are stopped at the floors by suitable automatic means and, more particularly, to systems of this character which are operated at relatively low speeds of the order of 100 to 200 feet per minute.

Although not limited thereto, our invention is particularly applicable to elevators of the geared drive type in which the hoisting drum is driven through suitable gearing by a constant speed alternating current motor. The motors usually provided in such installation have dropping speed-torque characteristics resulting in a variation of the car speed dependent upon the elevator load. If the motor is disconnected and the brake applied at the same fixed distance in advance of the floor each time, the car will coast or drift against the retarding torque of the brake for different distances before it stops, depending upon the car load and its direction of operation. Hence, the car may stop level with the floor when bearing one load and may stop short of or beyond the floor when bearing other loads. In order to obtain reasonably good accuracy in stopping at the floors, the brake torque must be set high in proportion to the motor capacity so that the car will coast or drift only a very short distance after the application of the brake. This results in exceedingly abrupt stops.

In order to minimize the abruptness of the stops, it is necessary to reduce the brake torque. This increases the drift of the car which results in much wider variations in the accuracy of the stops between maximum and minimum loads so that it is not practical to do this except in connection with elevators of low capacity and speed.

Therefore one object of our invention is to provide a system by which it is possible to use a reduced brake torque and then reduce the variation in the coasting or drifting of the car so as to obtain a comparative soft stop with good accuracy for the whole range of loads on the motor caused by the loading of the car and its direction of operation.

Another object is to provide means for causing the brake to be applied to the motor at a distance from the floor proportionate to the loading and direction of operation of the car so that it will coast or drift into a stop approximately level with the floor at which it is to load or unload.

Another object is to provide for so controlling the operation of a mechanically applied-electromagnetically released brake for an elevator car that the electric power for the motor and the brake may be cut off at the same time when the

car is a fixed distance from a floor at which a stop is to be made and to delay the action of the brake plunger thereafter for a length of time proportionate to the loading and direction of operation of the car so that it will coast into and stop approximately level with the floor.

A further object is to provide an elevator system having a brake with a load measuring device having amplifying characteristics which may be used for so controlling the brake system, that the apparatus will not be overly sensitive to speed, time or temperature changes and in which it will not be necessary to work to close tolerances in adjusting the apparatus.

15 It is also an object to provide a stopping system for elevator cars which shall be simple and inexpensive to install, operate and maintain in operation and which will be effective and long lived in service.

20 For a better understanding of our invention, reference may be had to the accompanying drawings, in which:

Figure 1 illustrates an elevator installation embodying our invention;

25 Fig. 2 is a straight line representation of the power and control circuits for the car illustrated in Fig. 1;

Fig. 3 is a straight line representation of the circuit for a tachometer generator used in connection with the control system in operating the elevator brake; and

30 Fig. 4 is a key representation of the relays embodied in Figs. 2 and 3, illustrating the coils and contact members disposed in horizontal alignment in their positions in the straight line circuits so that their locations therein may be readily determined.

Referring more particularly to the drawings, we have illustrated in Fig. 1 an elevator car C as disposed in a hatchway 1 and supported by a cable 2 passing over a hoisting drum 3 to a suitable counterweight 4. The hoisting drum is mounted on a shaft 5 disposed to be driven by an electric motor HM. A suitable gear reducing

45 mechanism 6 is connected with the shaft 5 to secure an appropriate speed of the car when the motor HM is in operation. A brake device having a brake 7 operated by an electromagnetic coil BC and a spring 9 is provided for stopping the car and holding it at any floor at which a stop is made. As shown, the spring applies the brake, and the coil, when energized, releases the brake. Any suitable form of electromechanical brake may be used instead of the particular form

50 illustrated.

The hoisting motor HM is illustrated as a three-phase single speed alternating current motor comprising a stator having windings 11, 12 and 13 and a rotor 14. The stator windings may be connected to a suitable alternating current supply represented by the conductors L1, L2 and L3 (Fig. 2) by means of an up direction switch U and a down direction switch D and a car running relay M. Although a motor of this character is called a constant speed motor, it is well known that its speed will vary somewhat in accordance with the loading and direction of operation of the car.

A car switch CS is mounted in the car for starting it and for causing it to be stopped at the various floors. Rotation of the switch in a clockwise direction will energize the down direction switch D to connect the motor windings to move the car downwardly, and rotation of the switch in counterclockwise direction will energize the up direction switch to connect the motor windings to move the car upwardly. Centering the car switch will cause its stopping system to stop the car at the next floor.

The energy for operating the direction switches, the stopping system, etc., may be supplied through a pair of conductors L+1 and L-1 which are connected for energization through a full-wave rectifier 17 to the supply conductors L1 and L3.

The means for stopping the car at the next floor after the car switch CS is centered for a stop comprises an inductor relay S provided with normally closed contacts in the holding circuit of the direction switches U and D. The inductor relay S is mounted on the top of the car (Fig. 1) and usually at one side thereof in position to pass closely adjacent to an up inductor plate UP and a down inductor plate DP at each floor when the car moves up and down in the hatchway. The inductor relay is provided with an energizing coil and a normally closed pair of stopping contacts S1. The inductor plates are constructed of magnetic material and are mounted in the hatchway in a position to cooperate with the relay and open its contacts when its coil is in an energized condition as the car approaches the inductor plates. We have shown inductor plates for only one floor, but it is to be understood that similar inductor plates will be mounted in the hatchway at each floor.

When the car switch CS is closed, one of the direction switches is energized first by a circuit through the car switch and next by a self-holding circuit through its own self-holding contacts and the normally closed contacts of the inductor relay. The center point of the car switch is connected to energize the inductor relay when the car switch is in its central position, so that the car will stop at the next floor after the switch CS is centered. Hence, when the car switch is centered for a stop, the inductor relay is energized, and, when it comes opposite the inductor plates at the next floor, it is operated to open its contacts in the holding circuit and deenergizes the direction switch. The deenergized direction switch opens the circuit for the hoisting motor and the brake.

When the motor circuit and the brake circuit are opened at the same time, the motor is deenergized immediately and the brake is applied immediately to stop the car. However, the car will drift or coast a short distance after the brake is applied and this amount of drift will depend upon the loading and direction of operation of the car. Under normal conditions the

car will stop approximately level with the floor, but at other times, it may overrun or underrun the floor. In general, with the normal speed of the car designed for, say, 100 feet per minute, the normal drift of the car will be approximately seven inches for a normal stop, and the automatic stopping means for the car, such as the inductor plates, will be set at such a point in the hatchway as to cut off the motor and the brake when the car is seven inches from the floor level.

However, when the car is moving upwardly with a full load and is brought to a stop, it may drift only three inches and thus stop four inches short of being level with the floor. On the other hand, with the same load down, the car may drift as much as eleven inches thus overrunning the floor as much as four inches.

In our invention, we cause the car to stop approximately level with the floor under all conditions by providing a means for delaying the starting movement of the brake plunger after the motor circuit and the brake circuit have been opened, for a length of time proportioned to the load on the motor (produced by the load on the car and its direction of operation) so that the brake will be applied to the motor at a point distant from the floor which will cause the car to drift into and stop level with the floor regardless of its load and direction of operation.

The means for delaying the starting movement of the brake plunger after the power is cut off the brake coil comprises means for "soaking" the brake coil above the saturation point of its core or magnetic circuit, by attaching a low discharge resistance circuit K to the brake coil, by attaching a high discharge resistance circuit P to the brake coil and by providing means for controlling the resistance value of the low discharge resistance circuit in accordance with the load on the hoisting motor.

The "soaking" of the brake coil is obtained by applying a large enough number of ampere turns to the brake coil, to run the flux up to a maximum value considerably above the saturation point of its core or magnetic circuit.

If desired, some other point in saturation may be used instead of that indicated by "soaking," just so there is always a constant point from which the delay may be started.

The low discharge resistance circuit K is connected in a circulatory circuit with the brake coil BC by the contacts M5 of the car running relay M, so that it will be connected with the brake coil only during stopping operations and will be disconnected at any time the hoisting motor is energized to run the car. The resistance circuit K is divided into a plurality of resistors R1, R2, R3, R4 and R5.

The high resistance discharge circuit P is permanently connected in circulatory relation with the brake coil BC and is never disconnected at any time. This circuit includes the resistor R6. The high discharge resistor circuit P is provided to give a slight time delay in the discharge of the brake coil after its power is cut off until the contacts M5 close to connect the low discharge resistance circuit K to the brake coil BC.

The purpose of the low discharge resistance circuit K is to delay the deenergization of the brake coil after the power to the brake coil circuit is broken and thus cause a delay in the starting of the brake plunger to apply the brake after the power is cut off the hoisting motor and the brake coil. The circuit K does not give an

appreciable time delay in the motion of the brake plunger but it alters the initiation of the motion of the plunger appreciably. Once the plunger starts it moves rapidly under the influence of the spring **9**, regardless of the brake discharge.

By varying the value of the resistance in the low discharge circuit **K**, the amount of time which expires between the cutting off of the power to the brake coil and the initial starting of the plunger to its brake-applying position may be varied. This is accomplished by using the resistor relays **1X, 2X, 3X** and **4X** to control the number of resistor sections **R1, R2, R3, R4** and **R5** left in the low discharge resistor circuit when the power is cut off for a stop. Each of the resistor relays is provided with a self-holding pair of contacts so that it locks in when energized and retains its position until all of the resistor relays are deenergized.

The load responsive relays **1H, 2H, 3H** and **4H** are used for controlling the number of resistor relays to be energized during a braking operation. A resistor **Q1** is disposed in series with the relay **1H** so that the relay may be adjusted to any desired amount.

The tachometer **G** is provided for controlling the load responsive relays **1H, 2H, etc.**, and its armature **GA** is mounted on the shaft **5** of the hoisting drum so that it will be rotated in accordance with the speed of the hoisting motor, whereby the output of the tachometer will correspond to the load on the car and its direction of operation.

In order that the tachometer **G** may give an amplified measurement of the loading of the car, it is provided with three field windings; that is, a separately excited field winding **GF**, a self-excited shunt field winding **GFE** and a series field winding **GFS**. The tachometer may be designed to give any result desired but it may be noted that one satisfactory design embodies a separately excited shunt field winding **GF** of 3600 turns developing 720 ampere turns; a self-excited shunt field winding **GFE** having 3600 turns and developing 720 ampere turns; and a series field **GFS**, with the four **H** relays as a load, being given 5800 turns at .4 ampere to develop 2320 ampere turns. A series field resistor **R10**, having a value of 500 ohms, may be provided to adjust the self-excited shunt field winding.

With the tachometer constructed along these lines it will give a much amplified output in proportion to the loading and direction of operation of the elevator car and this amplified output is used for operating the load responsive relays **1H, 2H, etc.** The **H** relays each have approximately the same operating characteristic. When the first one is operated it closes contacts, preparing the next one for operation, and it in turn will be operated when the voltage generated by the tachometer increases to a predetermined amount. When a speed and consequently load responsive relay **H** is operated it also closes contacts for energizing a resistor relay **X**, which in turn opens its contacts in the low resistance discharge circuit **K** and thereby increases the resistance in the circuit so that the discharge of the brake coil deenergizes it more quickly and thus permits the brake plunger to start its braking action more quickly.

The circuit for the armature **GA** of the tachometer embodies direction contacts of the up and the down direction relays **U** and **D** so that the armature will always be operated to produce

the same direction of voltage regardless of the direction of operation of the car.

A load timing relay **T**, having a drop-out of approximately two seconds, is provided for limiting the time of taking the load measurement to two seconds after the starting of the car; that is, you measure the load of the car by the action of the tachometer **G** for two seconds when the car starts, and then the relay **T** stops the operation. Then that measurement is used to allow the amount of resistance to be used in the load discharge circuit **K** to apply the brake at that point from which the car will drift into position level with the floor. When the measurement is completed at the end of two seconds, and the relay **T** times out, the load-responsive or measuring relays **H** which have responded to the measurement have operated their corresponding resistor relays **X**, and they have been locked in and thus hold their contacts in the resistor circuit **K** in the position to which they have been assigned until the next stopping operation is made.

A brake timing relay **F** is provided for restoring the resistor relays **X** to normal condition at the end of, say, one-half second after the motor and brake circuits are opened for a stop so that the starting of the brake plunger must take place within one-half second; that is, it will be assumed that the starting of the brake plunger will take place within less than one-half second and the brake timing relay is provided to limit the delay to that time.

It is believed that the invention may be better understood by an assumed operation of the apparatus.

It will be assumed that the car has stopped at the second floor on a down trip and has taken on several passengers, thus giving it approximately half a load. Under these conditions the load timing relay **T** is energized by the circuit **L+1, MC, T, L-1**. It will be assumed now that the attendant moves the car switch **CS** in clockwise direction, thereby energizing the down direction switch **D** and the car running relay **M** to start the car in the down direction by the circuit **L+1, M, D, CS1, L-1**. The energized running relay **M** closes its contacts **M1, M2, M3, M4** and **M7**, and opens its contacts **M5** and **M6**. The closed contacts **M1, M2, M3** prepare the motor circuits **L1, L2** and **L3** for operation. The closed contacts **M4** prepare the brake coil circuit for operation. The opened contacts **M5** disconnect the low discharge circuit **K** from the brake coil. The opened contacts **M6** deenergize the load timing relay **T** so that it starts timing out. The closed contacts **M7** energize the brake timing relay **F**, thus preparing it for the next braking action.

The energized down direction switch **D** closes its contacts **D1** to **D6**. The closed contacts **D3** complete a self-holding circuit for the relay **D** so that it will remain energized, even though the car switch is returned to its center position, until the stopping inductor relay **S** is operated to stop the car. The closed contacts **D1** and **D2** energize the windings of the hoisting motor **HM** by the circuit **L1, M1, D1, 12** to a point **18**; **L2, M2, D2, 11** to a point **19**; **L3, M3, 13** to the point **18**. The hoisting motor **HM** is now energized for operation. The closing of the contacts **D4** energizes the brake coil **BC** by the circuit **L+1, D4, BC, M4, L-1**. The energized brake coil **BC** releases the brake **7** and the car starts downwardly.

As the car starts downwardly, the hoisting motor shaft **5** starts the tachometer **G** in operation

and as the voltage produced by the tachometer builds up in accordance with the load in the car, the load measuring relay $1H$ is operated by the circuit $L+2$, $1H$, $Q1$, $L-2$. The energized relay $1H$ closes its contacts $1H1$, thus energizing the resistor relay $1X$ by the circuit $L+1$, $F1$, $1X$, $1H1$, $L-1$. The energized relay $1X$ closes its self-holding contacts $1X2$ so that it will be locked in until the end of the next braking operation and also opens its contacts $1X1$, thereby inserting the resistor section $R2$ in the low discharge resistance circuit K . Of course this resistor $R1$ has no effect on this circuit at present because the contacts $M5$ are open.

When the relay $1H$ was energized it also closed its contacts $1H2$, thereby preparing relay $2H$ for energization. It will be assumed now that the load in the car is sufficient to increase the voltage output of the tachometer G to the point where it also energizes the load responsive relay $2H$ by the circuit $L+2$, $1H2$, $2H$, $Q2$, $L-2$. The energized relay $2H$ closes its contacts $2H1$ and $2H2$. The closed contacts $2H2$ prepare the relay $3H$ for operation if and when the voltage produced by the tachometer is sufficient to operate it. The closed contacts $2H1$ energize the resistor relay $2X$ by the circuit $L+1$, $F1$, $2X$, $2H1$, $L-1$. The energized relay $2X$ closes its self-holding contacts $2X2$ and opens its contacts $2X1$, thus inserting the resistor $R3$ in the low discharge resistance circuit K .

By the foregoing operation it is seen how the load in the car is measured at the start of a movement from one stop to the next stop, and how the resistor sections in the low discharge 35 brake coil circuit are set up for use when the next stop is made in accordance with the speed of the hoisting motor as determined by the load on the car and its direction of operation at the start of the car movement. This operation takes 40 place rather rapidly and, while it is going on, the load timing relay T has been timing out so that now, at the end of two seconds, that relay times out and opens its contacts $T1$ in the circuit to the tachometer armature GA , thus preventing 45 the tachometer armature GA from providing any further measuring voltage for operating the load responsive relays, also the heating effect of the current is discontinued, making the system substantially independent of heating.

When the tachometer G is deenergized by the opening of the contacts $T2$, that reduces the voltage in the load responsive relays H to zero and they return to their normal positions ready for the next operation.

It will also be apparent that, in view of the three field windings used on the tachometer, the voltage resulting from its operation will be an amplified measurement of the load on the hoisting motor caused by the load in the car and its direction of operation.

It will be assumed now that the attendant centers the car switch to stop the car at the next floor. This operation energizes the stop inductor relay S by the circuit $L+1$, S , $CS2$, $L-1$. The energized inductor relay S is now ready for operation to stop the car at the next floor. As the car moves in to the next floor, it moves the inductor relay S into close relation with the down stopping plate DP and the influence of that plate causes the inductor relay to open its contacts $P1$, thereby deenergizing the car running relay M and the down direction switch D to stop the car. The deenergized relay M opens its contacts $M1$, thereby deenergizing the brake timing relay F .

and this relay will time out after the expiration of one-half second for the purpose of limiting the delay in the start of the braking action to that period and for then returning the resistor relays to their normal condition.

The deenergized relay D opens its contacts $D1$ to $D6$. The opening of the contacts $D1$ and $D2$ deenergizes the hoisting motor HM , and the opening of the contacts $D4$ deenergizes the circuit to the brake coil BC . Inasmuch as the brake coil is "soaked" or oversaturated, the opening of the contacts $D4$ does not cause the brake plunger 7 to start movement immediately. The reason for this is that the opening of the circuit to the brake coil brings the circulatory circuit P into operation. The resistor circuit P insures the giving of a slight time delay in the discharge of the brake coil until the contacts $M5$ close and connect the low discharge resistor K to the brake coil BC .

It will be recalled that the resistors $R2$ and $R3$ have been inserted in the low discharge resistance circuit K in accordance with the loading and direction of operation of the car at the start of this movement. Therefore, as the brake coil now discharges through the low resistance discharge circuit K , the rate of discharge will be such that the brake plunger will not be released to start its brake applying movement until after the expiration of a length of time corresponding to the load on the motor caused by the load in the car and its direction of operation at the start of its movement down from the second floor.

When the discharge of the brake coil through the low resistance discharge circuit K decreases sufficiently, the brake plunger starts and moves instantly to apply the brake under the influence of the spring S and the car coasts into and stops level with the floor. This occurs because the distance coasted by the car corresponds to the loading and direction of operation of the car, and this distance was set by the tachometer, energizing the measuring relays to operate the resistor relays in accordance with the load and direction of operation which occurred in the first two seconds of its movement toward this floor.

Assuming now that the half-second timing out period of the brake timing relay F has expired, that relay opens its contacts $F1$, thereby deenergizing the resistor relays $1X$ and $2X$ and restoring them to normal condition for the next braking operation.

Also, the closed contacts $M6$ energize the load timing relay T to prepare it for operation during the next starting action of the car.

If a heavier load, say full load, had entered the car at the second floor, then the speed would have been higher and the tachometer generator voltage would have been higher and all four relays $1H$ to $4H$ would have been energized. Under these conditions resistor relays $1X$ to $4X$ would have picked up and locked in thus inserting a high resistance in the low discharge circuit connected to the brake coil. The brake would set quickly under these conditions and the car, due to its load, would slide the correct distance through the brake to stop the car with its platform at floor level.

If the car had been empty, the motor would have had to lift part of the weight of the counterweight, the speed would have been low, and none or possibly only $1H$ of relays $1H$ to $4H$ would have closed thereby connecting a small amount of resistance in the low discharge resistance cir-

cuit. The small amount of resistance would cause the brake coil to become deenergized more slowly, so the car would be closer to the floor when the brake finally does engage, and there would be less distance available to stop the car in before floor level. However, when empty, the car stops quicker and a level stop would again occur. The other relays, H and X, will give intermediate brake application time corresponding to intermediate loads.

From the above it will be seen that we have provided a simple and effective means for measuring the load on a hoisting motor caused by the load in the car and its direction of operation and have used this loading or resultant speed for measuring the time or the distance at which a brake plunger should be released to effect the stopping of a car level with the floor.

It will also be apparent that the apparatus is simple and efficient in operation and that the tachometer and parts responsive thereto provide a generous range of voltage for operating the measuring relays so that adjustment of the relay pick-up will not be critical nor seriously affected by ambient temperature variations. Although we have illustrated and described only one specific embodiment of our invention, it is to be understood that changes therein and modifications thereof may be made without departing from the spirit and scope of the invention.

We claim as our invention:

1. In an elevator system for operating a car past a floor, a motor for operating the car, a brake for the motor, said brake having a spring applying means and a brake coil releasing means, circuits for the motor and the brake coil, control means for energizing the circuits for the motor and the brake coil to start the car and for deenergizing said circuits when the car is a predetermined distance from the floor to stop the car thereat, a low discharge resistance circuit for the brake coil, means responsive to the speed of the motor for adjusting the value of the resistance in the low discharge resistance circuit in accordance with the load on the car and its direction of operation, and means responsive to operation of the control means to stop the car for connecting the low discharge circuit to the brake coil and keeping it connected thereto during the stopping operation, whereby the deenergization of the brake coil will be delayed to cause application of the brake at a point in the car travel which will cause the car to stop approximately level with the floor.

2. In an elevator system for operating a car past a floor, a motor for operating the car, a brake for the motor, said brake having a spring applying means and a brake coil releasing means, circuits for the motor and the brake coil, control means for energizing the circuits for the motor and the brake coil to start the car and for deenergizing said circuits when the car is at a predetermined distance from the floor to stop the car thereat, a discharge resistance circuit for the brake coil, a tachometer connected for operation by the motor, said tachometer having a series field winding, a self-excited shunt field winding and a separately excited shunt field winding to cause it to give a greater than one-to-one measure of the load on the hoisting motor, means responsive to the operation of the tachometer for adjusting the value of the resistance in the discharge resistance circuit in accordance with the load on the car and its direction of operation, and means responsive to operation of the

control means to stop the car for connecting the low discharge circuit to the brake coil and keeping it connected thereto during the stopping operation, whereby the deenergization of the brake coil will be delayed to cause application of the brake at a point in the car travel which will cause the car to stop approximately level with the floor.

3. In an elevator system for operating a car past a floor, a motor for operating the car, a brake device for decelerating the car to a stop, said device having a spring-applied brake and a brake coil for moving the brake to its off position and for releasing it to its on position, circuits for the motor and the brake coil, control means for energizing the circuits for the motor and the brake coil to start the car, a discharge resistance circuit associated with the brake coil for delaying the deenergization of the brake coil after the brake coil circuit is deenergized, means responsive to the speed of the hoisting motor for a predetermined time after the car starts for adjusting the value of the resistance in the discharge resistance circuit to thereby prepare the discharge circuit to delay the deenergization of the brake coil after the brake coil circuit is deenergized for the next stop for a length of time commensurate with the load on the car and its direction of operation, and a stopping means for deenergizing the motor and brake coil circuits and for connecting the discharge circuit to the brake coil when the car arrives at a predetermined distance from the floor to cause the car to stop thereat.

4. In an elevator system for operating a car past a floor, a motor for operating the car, a brake device for decelerating the car to a stop, said device having a spring-applied brake and a brake coil for moving the brake to its off position and for releasing it to its on position, circuits for the motor and the brake coil, control means for energizing the circuits for the motor and the brake coil to start the car, a discharge resistance circuit associated with the brake coil for delaying the deenergization of the brake coil after the brake coil circuit is deenergized, a speed responsive device connected for operation by the motor for measuring the speed of the motor as it is affected by the load on the car and its direction of operation during the starting action of the car, means responsive to operation of the speed device for adjusting the value of the resistance in the discharge resistance circuit and thereby prepare the discharge circuit to delay the deenergization of the brake coil after the brake coil circuit is deenergized for the next stop for a length of time commensurate with the load on the car and its direction of operation, and a stopping means for deenergizing the motor and brake coil circuits and for connecting the low discharge circuit to the brake coil when the car arrives at a predetermined distance from the floor to cause the car to stop thereat.

5. In an elevator system for operating a car past a floor, a motor for operating the car, a brake device for decelerating the car to a stop, said device having a spring-applied brake and a plunger with a brake coil for moving the brake to its off position, circuits for the motor and the brake coil, control means for energizing the circuits for the motor and the brake coil to start the car, a discharge resistance circuit for the brake coil, a tachometer connected for operation by the motor for measuring the speed of the motor as it is affected by the load on the

car and its direction of operation, means responsive to operation of the tachometer for adjusting the value of the resistance in the discharge resistance circuit to accord with the load on the car and its direction of operation for preparing the coil to delay its release of the plunger and thereby the application of the brake for a length of time sufficient to cause the car to stop approximately level with the floor when the next stop is made, and a stopping means for deenergizing the motor and brake coil circuit and for connecting the low discharge resistance circuit prepared by the adjusting means to the brake coil when the car arrives at a predetermined distance from the floor to cause the car to stop thereat.

6. In an elevator system for operating a car past a floor, a motor for operating the car, a brake device for decelerating the car to a stop, said device having a spring-applied brake and a plunger with a brake coil for moving the brake to its off position, circuits for the motor and the brake coil, control means for energizing the circuits for the motor and the brake coil to start the car, a discharge resistance circuit for the brake coil, a tachometer connected for operation by the motor for measuring the speed of the motor as it is affected by the load on the car and its direction of operation, a load timing device for rendering the tachometer effective for a predetermined length of time when the car is started, means responsive to operation of the tachometer for adjusting the value of the resistance in the discharge resistance circuit to accord with the load on the car and its direction of operation for preparing the coil to delay its release of the plunger and thereby the application of the brake for a length of time sufficient to cause the car to stop approximately level with the floor when the next stop is made, and a stopping means for deenergizing the motor and brake coil circuits and for connecting the low discharge circuit to the brake coil when the car arrives at a predetermined distance from the floor to cause the car to stop thereat.

7. In an elevator system for operating a car past a floor, a motor for operating the car, a brake device for decelerating the car to a stop, said device having a spring-applied brake and a plunger with a brake coil for moving the brake to its off position, circuits for the motor and the brake coil, control means for energizing the circuits for the motor and the brake coil to start the car, a stopping means for deenergizing the motor and brake coil circuits and when the car arrives at a predetermined distance from the floor in making a stop, a discharge resistance circuit for the brake coil, a tachometer connected for operation by the hoisting motor, having a series field winding, a self-excited shunt field winding and a separately excited shunt field winding to cause it to give a greater than one-to-one measure of the load on the hoisting motor, means responsive to operation of the tachometer for varying the value of the resistance in accordance with the load on the car and its direction of operation, whereby the action of the coil will delay the release of the plunger for a length of time sufficient to cause the car to stop approximately level with the floor, connecting the low discharge circuit to the brake coil, a load timing device responsive to starting and stopping of the car for limiting the operation of the tachometer to a predetermined length of time.

8. In an elevator system for operating a car past a floor, a motor for operating the car, a brake

device for decelerating the car to a stop, said device having a spring-applied brake and a plunger with a brake coil for moving the brake to its off position, circuits for the motor and the brake coil, control means for energizing the motor and brake coil circuits to start the car and for deenergizing the said coil circuits to cause the car to stop at the floor, a discharge resistance circuit for the brake coil, a tachometer connected for operation by the hoisting motor, means responsive to operation of the tachometer for adjusting the value of the resistance in the discharge circuit to accord with the load on the car and its direction of operation for delaying the release of the plunger by the coil for a length of time sufficient to cause the car to stop approximately level with the floor, means responsive to operation of the control means in stopping the car for connecting the low discharge circuit to the brake coil, and a load timing device responsive to starting and stopping of the car for limiting the operation of the tachometer to a predetermined length of time.

9. In an elevator system for operating a car past a floor, a motor for operating the car, a brake device for decelerating the car to a stop, said device having a spring-applied brake and a plunger with a brake coil for moving the brake to its off position, circuits for the motor and the brake coil, control means for energizing the circuits for the motor and the brake coil to start the car, a stopping means for deenergizing the motor and brake coil circuits when the car arrives at a predetermined distance from the floor in making a stop, a discharge resistance circuit for the brake coil, a tachometer connected for operation by the hoisting motor, having a series field winding, a self-excited shunt field winding and a separately excited shunt field winding to cause it to give a greater than one-to-one measure of the load on the hoisting motor, means responsive to operation of the tachometer for varying the value of the resistance in the discharge resistance circuit to accord with the load on the car and its direction of operation, whereby the action of the coil will delay the release of the plunger for a length of time sufficient to cause the car to stop approximately level with the floor, means responsive to operation of the stopping means for connecting the low discharge circuit to the brake coil, and a load timing device responsive to starting and stopping of the car for limiting the effective operation of the tachometer to a predetermined length of time.

10. In an elevator system for operating a car past a floor, a motor for operating the car, a brake device for decelerating the car to a stop, said device having a spring-applied brake and a plunger with a brake coil for moving the brake to its off position, circuits for the motor and the brake coil, control means for energizing the circuits for the motor and the brake coil to start the car, a stopping means for deenergizing the motor and brake coil circuits when the car arrives at a predetermined distance from the floor in making a stop, a low discharge resistance circuit for the brake coil, a tachometer connected for operation by the hoisting motor, a plurality of resistors associated with the low discharge circuit, means responsive to operation of the tachometer for inserting a number of resistors corresponding to the output of the tachometer in the low discharge circuit for delaying the release of the plunger after the brake circuit is deenergized for a length of time commensurate with the load on the car and its direc-

tion of operation, means responsive to operation of the stopping means for connecting the low discharge circuit as conditioned by the resistors to the brake coil, and a load timing device responsive to starting and stopping of the car for limiting the operation of the tachometer to a predetermined length of time when the car starts operating.

11. In an elevator system for operating a car past a floor, a motor for operating the car, a brake device for decelerating the car to a stop, said device having a spring-applied brake and a plunger with a brake coil for moving the brake to its off position, circuits for the motor and the brake coil, a switch for energizing the circuits for the motor and the brake coil to start the car, a stopping means for deenergizing the motor and brake coil circuits to stop the car, a discharge resistance circuit for the brake coil, a tachometer connected for operation by the hoisting motor, a plurality of measuring relays connected for accumulative operation in accordance with the output of the tachometer, a plurality of resistors associated with the low discharge circuit, one for each measuring relay, means responsive to operation of the measuring relays for inserting their resistors in the low discharge circuit for delaying the release of the plunger after the brake circuit is deenergized for a length of time commensurate with the load on the car and its direction of operation, means responsive to operation of the stopping means for connecting the low discharge circuit as conditioned by the resistors to the brake coil, and a load timing device responsive to the operation of the car for rendering the tachometer effective to measure the speed of the hoisting motor resulting from the effect of the load on the car and its direction of operation for a predetermined length of time upon the starting of the car.

12. In an elevator system for operating a car past a floor, a motor for operating the car, a brake device for decelerating the car to a stop, said device having a spring-applied brake and a plunger with a brake coil for moving the brake to its off position, circuits for the motor and the brake coil, control means for energizing the circuits for the motor and the brake coil to start the car, a stopping means for deenergizing the motor and brake coil circuits when the car arrives at a predetermined distance from the floor in making a stop, a discharge resistance circuit for the brake coil, a tachometer connected for operation by the hoisting motor, a plurality of measuring relays connected for accumulative operation in accordance with the output of the tachometer, a plurality of resistors associated with the low discharge circuit, one for each measuring relay, means responsive to operation of the measuring relays for inserting their corresponding resistors in the low discharge circuit for delaying the release of the plunger after the brake circuit is deenergized for a length of time commensurate with the load on the car and its direction of operation, means responsive to operation of the stopping means for connecting the low discharge circuit as conditioned by the resistors to the brake coil, and a load timing device responsive to starting and stopping of the car for limiting the operation of the tachometer to a predetermined time.

13. In an elevator system for operating a car past a floor, a motor for operating the car, a brake device for decelerating the car to a stop, said device having a spring-applied brake and a plunger with a brake coil capable of energizing its magnetic circuit to approximately its saturation

point for moving the brake to its off position, circuits for the motor and the brake coil, a switch for energizing the circuits for the motor and the brake coil to start the car, a stopping means for deenergizing the motor and brake coil circuits when the car arrives at a predetermined distance from the floor in making a stop, a low discharge resistance circuit for the brake coil, a high discharge resistance circuit permanently connected to the brake coil, a tachometer connected for operation by the hoisting motor, said tachometer having a series field winding, a self-excited shunt field winding and a separately excited shunt field winding to cause it to give a greater than one-to-one measure of the load on the hoisting motor, a plurality of measuring relays connected for accumulative operation in accordance with the output of the tachometer, a plurality of resistors associated with the low discharge circuit, one for each measuring relay, means responsive to operation of the measuring relays for inserting their resistors in the low discharge circuit for delaying the release of the plunger after the brake circuit is deenergized for a length of time commensurate with the load on the car and its direction of operation, means responsive to operation of the stopping means for connecting the low discharge circuit as conditioned by the resistors to the brake coil, and a load timing device responsive to starting and stopping of the car for limiting the operation of the tachometer to a predetermined period when the car starts operating.

14. In an elevator system for operating a car past a floor, a motor for operating the car, a brake device for decelerating the car to a stop, said device having a spring applied brake and a plunger with a brake coil capable of energizing its magnetic circuit to approximately its saturation point for moving the brake to its off position, circuits for the motor and the brake coil, a switch for energizing the circuits for the motor and the brake coil to start the car, a stopping means for deenergizing the motor and brake coil circuits when the car arrives at a predetermined distance from the floor in making a stop, a low discharge resistance circuit for the brake coil, a high discharge resistance circuit permanently connected to the brake coil for delaying the deenergization of that coil when a stop is being made until the low discharge resistance circuit is connected to the brake coil, a tachometer connected for operation by the hoisting motor, a plurality of measuring relays connected for accumulative operation in accordance with the output of the tachometer, a plurality of resistors associated with the low discharge circuit, one for each measuring relay, a plurality of resistor relays provided with self-holding means, one of said relays for each measuring relay and responsive to operation of that measuring relay for inserting the resistor corresponding to that measuring relay in the low discharge circuit, whereby the value of the resistance in the low discharge circuit will delay the release of the plunger after the brake circuit is deenergized for a length of time commensurate with the load on the car and its direction of operation, means responsive to operation of the stopping means for connecting the low discharge circuit as conditioned by the resistors to the brake coil, and a load timing device responsive to starting and stopping of the car for limiting the operation of the tachometer to a predetermined period when the car starts operating.

15. In an elevator system for operating a car past a floor, a motor for operating the car, a

brake device for decelerating the car to a stop, said device having a spring-applied brake and a plunger with a brake coil for moving the brake to its off position, circuits for the motor and the brake coil, a switch for energizing the circuits for the motor and the brake coil to start the car, a stopping means for deenergizing the motor and brake coil circuits when the car arrives at a predetermined distance from the floor in making a stop, a low discharge resistance circuit for the brake coil, a high discharge resistance circuit permanently connected to the brake coil for delaying the deenergization of that coil when a stop is being made until the low discharge resistance circuit is connected to the brake coil, a tachometer connected for operation by the hoisting motor, a plurality of measuring relays connected for accumulative operation in accordance with the output of the tachometer, a plurality of resistors associated with the low discharge circuit, one for each measuring relay, a plurality of resistor relays provided with self-holding means, one of said relays for each measuring relay and responsive to operation of that measuring relay for inserting the resistor corresponding to that measuring relay in the low discharge circuit, whereby the value of the resistance in the low discharge circuit will delay the release of the plunger after the brake circuit is deenergized for a length of time commensurate with the load on the car and its direction of operation, means responsive to operation of the stopping means for connecting the low discharge circuit as conditioned by the resistors to the brake coil, and a brake timing relay for returning the resistor relays to their normal condition at the end of a predetermined time after the brake circuit is deenergized.

16. In an elevator system for operating a car past a floor, a motor for operating the car, a brake device for decelerating the car to a stop, said device having a spring-applied brake and a plunger with a brake coil capable of energizing its magnetic circuit to approximately its saturation point for moving the brake to its off position, circuits

for the motor and the brake coil, a switch for energizing the circuits for the motor and the brake coil to start the car, a stopping means for deenergizing the motor and brake coil circuits when the car arrives at a predetermined distance from the floor in making a stop, a low discharge resistance circuit for the brake coil, a high discharge resistance circuit permanently connected to the brake coil for delaying the deenergization of that coil when a stop is being made until the low discharge resistance circuit is connected to the brake coil, a tachometer connected for operation by the hoisting motor, said tachometer having a series field winding, a self-excited shunt field winding and a separately excited shunt field winding to cause it to give a greater than one-to-one measure of the load on the hoisting motor, a plurality of measuring relays connected for accumulative operation in accordance with the output of the tachometer, a plurality of resistors associated with the low discharge circuit, one for each measuring relay, a plurality of resistor relays provided with self-holding means, one of said relays for each measuring relay and responsive to operation of that measuring relay for inserting the resistor corresponding to that measuring relay in the low discharge circuit, whereby the value of the resistance in the low discharge circuit will delay the release of the plunger after the brake circuit is deenergized for a length of time commensurate with the load on the car and its direction of operation, means responsive to operation of the stopping means for connecting the low discharge circuit as conditioned by the resistors to the brake coil, a load timing device responsive to starting and stopping of the car for limiting the operation of the tachometer to a predetermined period when the car starts operating, and a brake timing relay for returning the resistor relays to their normal condition at the end of a predetermined time after the brake circuit is deenergized.
